UNITED STATES PATENT OFFICE.

THOMAS JEFFERSON GOODWIN, OF WACO, TEXAS.

AUTOMOBILE-COOLING SYSTEM.

1,277,909.

Specification of Letters Patent. Patented Sept. 3, 1918.

Application filed September 22, 1917. Serial No. 192,720.

To all whom it may concern:

Be it known that I, THOMAS J. GOODWIN, a citizen of the United States, residing at Waco, in the county of McLennan and State 5 of Texas, have invented new and useful Improvements in Automobile-Cooling Systems, of which the following is a specification.

This invention is an improved cooling apparatus or system especially designed for 10 cooling the internal combustion engine of an automobile, the object of the invention being to provide an improved cooling system of this kind which embodies means for cooling the circulatory water in the radiator by 15 forcing air therethrough and also embodies means for directly cooling the engine by subjecting the same to the action of a blast of air.

A further object of the invention is to 20 provide an improved cooling apparatus or system of this character which is extremely cheap and simple and which can be readily installed in an automobile.

The invention consists in the construction, 25 combination and arrangement of devices hereinafter described and claimed.

In the accompanying drawings:

Figure 1 is partly an elevation and partly 30 a sectional view of an internal combustion cooling apparatus constructed and arranged in accordance with my invention.

Fig. 2 is an elevation of the same, at right-angles to Fig. 1 and showing the casing of 35 the rotary fan partly removed and in section.

Fig. 3 is a vertical sectional view of the same.

Fig. 4 is a horizontal sectional view of the same.

40 In the embodiment of my invention I provide a radiator 1 through which the water for cooling the engine cylinders by circulation through the water jackets also circulates in the usual manner. The radiator is 45 provided with a centrally arranged inner tubular wall 2 of considerable diameter which connects the front and rear walls of the radiator and is open at the ends for the passage of air therethrough. A screen 3 50 covers the front end of the inner tubular wall or air passage and prevents trash from passing therethrough. On the rear wall of the radiator at opposite sides of the said air passage are vertically arranged guide strips 4 55 which have guide grooves 5 in their opposing sides.

The casing 6 of a revoluble blower or fan 7 is provided at opposite sides with arms 8 which slidably engage in the grooves of the guide strips and hence adapt the blower or fan for vertical movement on the rear side of the radiator, the fan casing being arranged opposite the rear end of the central air passage of the radiator and being of less diameter than said air passage. On 60 the rear side of the radiator is a lug 8'. A screw 9 which is vertically arranged passes through and engages in a threaded opening of the lug, the lower end of the screw being swivelly connected as at 9^a to the upper side 65 of the casing of the fan or blower. A spring 10 is arranged around the screw and bears between the fan or blower casing and the lug and serves to cushion the fan or blower casing and to prevent rattling and to also 70 exert a constant downward pressure thereon.

The revoluble member of the fan or blower is indicated at 11 and has a shaft 12 which is mounted in bearings in the front and rear sides of the casing, the said shaft extending rearwardly from the casing and being provided with an exteriorly arranged fan 13 and also with a peripherally grooved pulley 14, the latter being in practice connected to a corresponding pulley on the engine shaft by means of an endless belt 14' so that the revoluble member of the blower fan and also the exteriorly arranged fan are both driven by the motor. The casing of the blower fan is provided with a discharge 80 nozzle 15 which is connected by a flexible hose 16 of suitable length with the intake end of a tube 17, said tube being arranged and extending downwardly and in one side 85 of the radiator and being provided with air discharge apertures 18. An air discharge nipple 19 is provided for the radiator at a point a suitable distance above the level of the water therein.

90 In the operation of my invention the blast 100 of air discharged by the fan or blower passes through the pipe 17 and by reason of the apertures therein is forced through the water in the radiator, at various elevations so that the water in the radiator is directly 105 cooled by the passage and forcing of the air jets therethrough. The exteriorly arranged fan 13 serves to direct a blast of air directly on the exterior of the cylinders of the engine, as will be understood, so that my 110 cooling apparatus directly cools the air by circulation through the water jackets of the

engine and through the radiator and also serves to directly air cool the engine cylinders from the exterior thereof.

By the provision of the guide strips on the 5 rear side of the radiator and by the construction of the fan or blower casing with the arms which engage said guide strips the fan or blower casing is detachably mounted on the radiator and is also arranged for 10 such slight vertical adjustment as may be required in order to keep the driving belt tight.

My improved cooling apparatus is simple in construction, is extremely compact and 15 may be installed in an automobile at slight cost.

While I have herein shown and described a preferred form of my invention, I would have it understood that changes may be 20 made in the form, proportion and construction of the several parts, without departing

from the spirit of my invention and within the scope of the appended claim.

Having thus described my invention, I claim:—

In apparatus of the class described, a radiator having an air passage therethrough and also provided, on its rear side, with vertical grooved guide strips at opposite sides of said opening, a blower for its casing 30 arranged on the rear side of the radiator opposite said passage and provided with attaching arms slidably engaged in the grooves of said strips, a duct leading from the blower casing into the radiator and terminating below the water level of the radiator, a vertical adjusting screw for the blower casing and a cushioning spring bearing 35 downwardly on the blower casing.

In testimony whereof I affix my signature. 40

THOMAS JEFFERSON GOODWIN.
